UNITED STATES PATENT OFFICE.

ALEXANDER E. BROWN, OF CLEVELAND, OHIO.

HOISTING AND CONVEYING MACHINE.

SPECIFICATION forming part of Letters Patent No. 400,188, dated March 26, 1889.

Application filed March 15, 1887. Serial No. 231,020. (No model.)

To all whom it may concern:

Be it known that I, ALEXANDER E. BROWN, of Cleveland, in the county of Cuyahoga and State of Ohio, have invented certain new and useful Improvements in Hoisting and Conveying Machines; and I do hereby declare that the following is a full, clear, and exact description thereof, reference being had to the accompanying drawings, making part of this application.

My invention relates to that class or type of hoisting and conveying machines in which the bucket or load to be lifted and traversed is suspended from a sheave-block, the laterally-projecting journal or axle-hubs of which are designed to be supported at certain times upon suspension or sustaining hooks, combined with the traveling carriage or machine of the apparatus.

Previous to my invention hoisting and conveying machines of this type have been made in which either the laterally-projecting journals of the sheave-block (from which the load is suspended) were supported at certain times in hooks or upon the supporting-shoulders, or some adjustable or movable device; but so far as I know no machine has ever been made of this type (in which the sheave-block has to be raised and lowered by the action of the hoist-rope under the control of the engineer) with any sort of positively-engaging load-sustaining device, which is only capable of manipulation by some one at or in the vicinity of the locality at which it may be designed to lower and dump the load.

In many kinds of work which may be otherwise successfully and desirably performed by hoisting and conveying machinery—such, for instance, as the digging of ditches or sewers, &c.—it is a great desideratum to provide for use a contrivance involving such principle of construction that while the operatives or the attendant at the locality where the loads are to be raised and lowered cannot effect the descent of the loaded bucket or vessel except with the co-operation of the engineer who has control of the hoisting and lowering cable; neither can the engineer who has control of this device permit or effect the descent of a loaded vessel or tub except with the knowledge and co-operation of an attendant located

in the vicinity at which the tub is to be lowered.

It will be seen that in a machine organized in such manner while loads supported by the sheave-block and the hoist-rope connected therewith cannot be lowered except with the knowledge and co-operation of an attendant located at the point of work, it is impossible for the engineer to lower a load, either through carelessness or from a misunderstanding of the usual signals, at a time when the descent of the load might cause an accident or injury to some of the men in the ditch or pit.

I have devised and successfully employed a contrivance which fulfills all the requirements of a perfectly-safe organization, capable, however, of expeditiously performing all the necessary operations of a hoisting and conveying machine; and my invention in this direction may be said to consist, essentially, in the combination, with the machine or carriage, of a hoisting and conveying apparatus of the type mentioned, of sustaining or supporting hooks adapted when in their normal position to positively engage with and hold up the projecting hubs of the sheave-block, and arranged and operating to permit the release of the latter whenever the load shall have been lifted by the engineer through the medium of the hoist-rope, for the purpose of allowing the descent of the sheave-block (and the load connected therewith) at the pleasure of an attendant, who may, in a suitable manner, manipulate the said load-sustaining hooks at any point along the line of the tramway.

To enable those skilled in the art to which my invention relates to make and use the same, I will now proceed to more fully describe it, referring by letters of reference to the accompanying drawings, which form a part of this specification, and in which I have shown my invention carried out in that form in which I have so far successfully practiced it, and which is about the best now known to me.

In the drawings, Figure 1 is a side or face view of a portion of a well-known form of trolley or traversing carriage for hoisting and conveying machines and showing my improvement applied thereto. Fig. 2 is an end or edge view of the same. Fig. 3 is a partial

side view showing one end of the tramway and particularly illustrating the mode of attachment of one end of the hoist-rope to a fixed anchorage device secured to said tramway.

5 In the three figures the same parts will be found designated by the same letters of reference.

10 A A represent the metallic sides or body portions of the traversing machine or carriage, and B the hoist-block, which is raised and lowered by the usual hoist-rope, R, that passes beneath and partially around its grooved wheel, and which is formed or provided with the usual laterally-projecting 15 hubs, C, which, when the hoist-block is at its highest elevation, are drawn up into and loosely fit within the semicircular housings D of the metallic plates A of the carriage.

20 The hoist-rope R, it will be understood, has one end secured or anchored to a metallic anchorage device, I', which, as shown, is securely bolted or secured at some fixed or predetermined point to the tramway T, near one end of the latter, (see particularly Fig. 3 of 25 the drawings,) and has its other end wound on the drum of the hoisting-engine, all in the usual and well-understood manner.

25 F represents a pair of supporting-hooks, which at their upper ends are made fast to a 30 journal or stud, G, which passes through and revolves within a suitable bearing-box, H, arranged about centrally near the upper part of the machine. These hooks, which are arranged to swing in close proximity to the 35 outer face of the side pieces, A A, of the machine, are formed, it will be seen, at their hook portions f, of such shape that the lower portions of the peripheries of the hub-like 40 projections C may rest within and be supported by said hook portions f, the latter embracing or encircling the portions to an extent nearly or quite equal to one-half of a circle.

45 One or both of the lower opposite ends or holes of the two hooks may be formed or provided with a hole, as seen at g, by means of which a hook, cord, or other device may be secured or applied for the purpose of permitting an attendant located at some distance below the machine to conveniently manipulate 50 said hooks in a manner and for a purpose to be presently explained.

55 I is a draw-bar or pull-bar, one end of which is pivoted to one of the hooks F, as shown at i, and the other end of which is formed or provided with a piston or face-plate, l, which works within a cylinder, L, one end of which is tied by a rod, m, to a fixed point on the machine, and within which is arranged a spiral or coil spring, o, against which the face-plate or piston l presses. This spring draw-bar device performs the function simply of pulling the hook constantly in the direction indicated by the arrow drawn at Fig. 1, for 65 the purpose of keeping it up to its normal or working position, the lowermost ends of the

hooks being shaped as shown, so that when drawn over by the spring draw-bar against stop P, (or into the position seen at Fig. 1,) the ascending hub device C, striking against 70 the lower surfaces of the hooks, will act upon them on the principle of a cam and swing them in an opposite direction to that indicated by the arrow at Fig. 1 until said hub-like devices shall have passed upwardly by 75 the extreme points of the hooks, when the latter, actuated by the spring draw-bar, will return to the position seen at Fig. 1, in which, whenever the hubs C shall have been slightly lowered, they will embrace and support said 80 hubs, as shown.

85 Of course, it will be obvious to the skilled mechanic that various changes as to the forms and proportions of the parts shown, as well as in the precise arrangement together 90 of the devices, may be made without changing the alleged novel principle of construction and mode of operation of my improved contrivance. I therefore wish it to be understood that I do not wish to limit my claim of invention to any precise details of structure so long as the machine embraces the novel characteristics hereinbefore explained.

95 Of course, some other means than the spring draw-bar may be employed for causing the hooks to be positively and reliably brought always into a working position, or the gravity of the hooks may be relied upon for this purpose, although I consider it better to have some actuating device to insure the 100 return always of the hooks to the proper position for the resting therein of the hubs of the hoist-block after the hooks shall have been pushed one side by the ascent of said block.

105 What I claim, broadly, as new, and desire to secure by Letters Patent, is—

The combination of the following-named instrumentalities: first, any suitable tramway; second, a tramway-carriage or trolley 110 mounted to travel on said tramway; third, a hoist-rope having one end secured to a stationary point of attachment and the other end connected with the hoist-engine in the usual manner; fourth, a sheave-block in engagement with said hoist-rope, and which is supported by said rope only when being raised or lowered; fifth, the hooks Ff, formed with depressed seats to accommodate the engaging devices of the sheave-block, and from 115 which said devices can be released only by lifting the sheave-block, and, sixth, suitable means for the manipulation of said hooks by an attendant, said combination of instrumentalities operating substantially in the 120 manner and for the purposes set forth.

125 In witness whereof I have hereunto set my hand this 31st day of August, 1886.

ALEXANDER E. BROWN.

In presence of—

E. T. SCOVILL,
CHAS. W. KELLY.
